UNITED STATES PATENT OFFICE

DAVID LEVINSON, OF CHICAGO, ILLINOIS, ASSIGNOR TO WILSON-WESTERN SPORTING GOODS COMPANY, OF CHICAGO, ILLINOIS, A CORPORATION OF DELAWARE

PROTECTIVE APPARATUS FOR ATHLETES

Application filed February 14, 1927. Serial No. 167,976.

My invention relates to protective apparatus for athletes, being more particularly concerned with the provision of protective harness for football players.

5 One of the objects of my invention is the provision of a unitary protective harness for football players which may be supported upon the body of the player independently of football trousers or other garments, but 13 which is also composed of novel elements which may be either worn separately or in conjunction with the various other parts of the harness.

Another object of my invention is the provision of a novel reinforced guard for football players, particularly adapted for protecting the thigh and having means for supporting said guard independently of the harness or trousers.

29 Another object of my invention is the provision of such a thigh guard having novel reinforcing means comprising a tension member which is light in weight, cheaply manufactured, and which does not require padding 25 or other means on the reinforcing itself to prevent injury to players.

Other objects and advantages of my invention will appear more fully from the following description and from the accompanying drawings in which similar characters of reference indicate similar parts throughout the several views.

Referring to the drawings:

Figure 1 is a front elevational view of an 35 embodiment of my football harness,

Figure 2 is a rear elevational view of the same.

Figure 3 is a front elevational view of my thigh guard and supporting pocket,

40 Figure 4 is a rear elevational view of the same,

Figure 5 is a cross sectional plan view on the line 10-10 of Figure 3,

Figure 6 is a side elevational view in cross 45 section taken on the line 11-11 of Figure 3,

Figure 7 is a front elevational view of my improved thigh guard,

Figure 8 is an enlarged cross sectional detail view taken on the line 13-13 of Figure 7.

50 Referring to Figures 1 and 2, 10 indicates

in its entirety my football harness which is adapted to be supported upon the body of the wearer without additional support from other garments such as trousers, etc., and my harness is preferably worn underneath football trousers which may be adapted to fit the wearer very closely, having no additional padding, projecting parts or loose folds of fabric which may be grasped by opponents during the play. If desired, the trousers may 55 be made of closely fitting fabric which is smooth and slippery to the touch, thereby aiding the player in eluding the grasp of his opponents.

Referring to Figure 1, 11 indicates a girdle 65 portion which is adapted to be drawn closely about the body of the player by means of the strap 12 and by the adjustable lacing at 13. Attached to the girdle 11, but supported independently upon the limbs of the player by 70 means of an elastic band 14, are the thigh guard supporters 15 having a pocket therein to support the thigh guards 16. Supported at the lower edge of the thigh guard supporters 15 are the knee pads 17, and it will 75 be noted that while all of these parts are essential to a complete protective harness, any of the same may be worn separately, if so desired, by the provision of separate means for supporting each of the same upon the 80 body of the wearer. For this purpose the trousers may be provided with a transverse raceway consisting of a tape having a plurality of spaced apertures located at proper height within the trousers to attach the pads 85 17 by means of the usual lacing. The trousers may also be provided with a pocket in front of each knee which is adapted to receive the knee pad 17, thereby providing separate supporting means for each of the elements of the 90 harness.

Having briefly outlined the different parts of my harness, I shall now describe in detail the thigh guard and thigh guard support which are claimed in the present application, 95 the other subject matter shown in Figs. 1 and 2 having been made the subject of divisional applications.

My thigh guard supporter comprises a pocket 53 preferably formed of a plurality 100

of pieces of strong, closely woven fabric 54 and 55 and including elastic tension means 56 for holding the same closely upon the limb of the player. The pieces of fabric 54 and 55 are of substantially trapezoidal shape, being slightly wider toward the top 57 to accommodate the increasing taper of the limb. The pocket 53 may be formed by the stitching 58 outlining a substantially rectangular pocket 10 and the extreme edges of the fabric may be joined together by turning both edges inward and stitching as at 59. The upper two edges of the pocket at 57 are, of course, separately hemmed in order to provide an opening for 15 the pocket and each piece of fabric 54 and 55 is provided with a plurality of aligned apertures 60 which may be provided with metal eyelets but which are preferably buttonholed in order to eliminate hard metallic surfaces 20 near the body of the wearer.

The elastic tension means 56 comprises a wide band 61 of strong elastic fabric, preferably consisting of rubber threads woven within a cover of a stretchable fabric. The 25 elastic band 61 extends from a point near the bottom of the guard supporter to a point near the top, being of substantially the same width as the length of the high guard itself which is contained within the pocket 53 in order that 30 the guard may be closely supported upon the limb of the wearer at all times. The elastic may be attached to the fabric 54 and 55 by any convenient method of stitching, but I prefer to use the method shown in Figure 35 5, in which two edges of the fabric 54 and 55 are turned in in the usual manner, the edge of the elastic 56 is inserted between the end folds, under which the elastic 56 is folded down upon the fabric 54 and the whole fixed 40 together by a single line of stitching passing through two plies of elastic and four plies of fabric.

The upper corners of the fabric 54 and 55 may be beveled as at 62 from the upper edge 45 of the elastic toward the edge of the pocket 53 in order to eliminate loose corners of fabric, and if desired the outer portion of the fabric at 63 between the stitches 58 and 59 may be left open at the top to form an auxiliary pocket for additional padding along the side of the thigh. The pocket 63 may be 55 wider than that shown in Figure 3, if desired, and may be filled with a strip of sponge-like rubber of substantially the same thickness or slightly less than the edge 64 of the thigh guard 65.

The thigh guard 65 consists of a substantially rectangular curved piece of fiber board or other relatively light and stiff material 60 having its corners rounded as at 66 and the upper inside corner 67 beveled slightly to avoid interference with the trunk of the wearer. The fiber board 70 is preferably coated with shellac or the like for the purpose 65 of increasing its waterproofing qualities, and

the guard is provided with cushion means 68 at its edge and reinforcing means 69 extending across midway between the ends of the guard.

The external edge of the fiber board 70 is provided with a plurality of spaced perforations for the purpose of permitting the stitching 72, and it will be obvious that the perforations may be spaced a distance equal to the spacing for which the sewing apparatus may be set. The edge of the fiber board 70 may then be provided with padding means in the form of a strip of felt 73 folded about both sides of the edge of the fiber board, and in order to protect the felt 73 from the edge of the fiber board, which is often quite sharp, a strip of fabric tape 74 may be interposed between the felt and the fiber board wherever desired and the whole fixed together by a line of stitching 72 extending completely about the fiber board 70, the ends of the felt being slightly overlapped as at 75.

As the fiber board is curved about a vertical axis it will be observed that the side edges of the thigh guard 65 act somewhat like the flanges upon a channelled member and no reinforcing is required in this direction. In order to reinforce the thigh guard against flattening or against further curvature, I provide tension reinforcing means 69 which 55 comprises a light and flat tension member extending across the front of the guard as at 76 about the guard and across the back thereof as at 77.

The tension member 69 is preferably tensioned upon the guard while the same is of the curvature desired and fixed thereon by a plurality of rivets 78, 79 and 80, and in order to avoid interference of the tension member 69 with the padding 73 the guard is provided with a pair of apertures 81 and 82 located at each side of the guard just within the edge of the padding 73, through which the tension member passes. While the tension member 69 may be made of leather, fabric or many other materials which are both light and of the required tensile strength, I prefer to use a thin strip of ordinary steel strap on account of the great tensile strength, relative thinness and light weight of the same.

The co-operation of my reinforcing member with the fiber board 70 is as follows:

When the fiber board 70 is subject to strains which tend to further curve the fiber board, it will be observed that the strain of this force is placed upon the portion 76 of the tension member which is located upon the exterior surface of the curved board. In such case the portion 76, which is held at both ends by the rivets 78 and 80, bears tightly against the curved side of the fiber board, the fiber board being in compression while the strap 76 is in tension. In the case of stresses tending to flatten the curved fiber board 70, the portions 77 of the tension member are placed in fur-

ther tension while the fiber board is placed under compression, the portions 77 being drawn taut as segments across the arc of curvature between the rivets 78, 79 and 80 respectively. It should be observed that the method shown, of passing the tension member 69 completely about the parts of the fiber board to be reinforced permits the permanent fastening of the tension member 69 to the fiber board by a small number of rivets. If desired, the internal portions 77 of the reinforcing member may be drawn taut across the arc of the curved portions of the fiber board between the rivets so that they will be in position to resist flattening forces at once, but I prefer to have the internal portions 77 curved so as to lie flat against the guard at all points.

I am aware that protective guards have been reinforced by metal members which are adapted to resist changes of curvature of the guard solely because of their stiffness, and I desire it to be understood that while I prefer to use a tension member of steel strap my invention is not limited to the use of metal members nor does my reinforcing member cooperate with the guard in the manner of stiff bracing members under flexure which are necessarily of considerable weight in order to obtain the desired stiffening qualities.

It should also be observed that by means of a plurality of fastening rivets my tension member is disposed in relatively close position to the fiber board of the guard so that the tension member cannot touch the limb 35 of the wearer and the curvature of the guard may be made substantially concentric to that of the limb to which it is to be applied, so that the guard may bear against the limb solely at its exterior edge which is protected by the felt padding 73. The padding 73 is adapted not only to protect the limb from the sharp edges of the fiber board but it is also adapted to protect the clothing from the exterior edges of the fiber board, and the 40 relatively thin reinforcing member 69 is disposed within the projecting edges 83 of felt padding both on the inside and outside of the guard, where it cannot injure the player.

For further protection, however, an additional felt pad 73^a may be fastened to the fiber board over the tension members 77 by stitching or other convenient fastening means.

The thigh guard 65 may be inserted within 55 the pocket 53 of the thigh guard supporter in the position shown in Figure 3, which illustrates the guard for the right leg. The leg may be inserted within a tube like aperture provided by the fabric 54 and the elastic 57, and the elastic being stretched to form a larger aperture, the thigh guard supporter may be slid into place with the thigh guard 65 disposed upon the forward part of the thigh and the elastic 56 extending about the 60 back of the leg and holding all parts of the

fabric and thigh guard closely against the leg. It should be noted that the method of forming the seam between the elastic and fabric as at 84 forms the interior of the thigh guard supporter without projecting seams which might produce discomfort to the wearer. 70

The thigh guard supporter is thus capable of being independently supported upon the leg of the player by the elastic 56 and when the upper edge 57 of the thigh guard supporter is laced to the girdle 11 by means of the apertures 52 and 60 the thigh guard supporter performs the additional function of holding down the girdle which might otherwise tend to slide upward. The double rows of apertures also provide adjustable means for the relative positions of the girdle and thigh guard supporter while the apertures 85 at the bottom of the thigh guard supporter provide means for supporting the knee pad 17. The lacing 86 which attaches the thigh guard supporter to the girdle 11 also serves to close the end of the pocket 53 thereby retaining the thigh guard 65 in fixed position within the pocket. If desired, additional means holding the thigh guard in the pocket may be provided in the form of apertures in the fabric 54, apertures in the fibre board 70 and a separate lacing passing through the same. 95

While I prefer to support my thigh guards as shown, I desire it to be understood that the guard 65 may also be supported in pockets upon the football trousers, or the football trousers may be provided with raceways consisting of strips of tape having buttonholed eyelets and the fabric 54 and 55 of the pocket may likewise be provided with buttonholed apertures along the side seams 59 for the purpose of lacing the pocket within the trousers. If desired, the elastic 56 may also be made adjustable by substituting an appropriate raceway for one of the seams 84 so that the tension of the elastic may be adjusted by lacing. 100

It will thus be observed that I have invented a protective harness for athletic purposes which is adapted to fit closely upon the body of the player and which is supported independently of trousers or any other garments. While separate units of my harness are capable of being used alone, the harness is preferably used in its entirety as the thigh guard supporter performs an additional function in maintaining the girdle in proper position. 115

My thigh guard is lighter and stronger than the thigh guards of the prior art by reason of the fact that I employ a tension bracing member which may be very light and thin as distinguished from the thigh guards employing members which brace by virtue of their stiffness. My thigh guard is also more effectively padded so as to protect the wearer and the players with whom he may 120 125 130

come in contact, as well as preventing the cutting or tearing of the clothing worn with the thigh guard.

While I have illustrated and described a specific embodiment of my invention, many modifications may be made without departing from the spirit of the invention, and I do not wish to be limited to the precise details of the construction set forth but desire to avail myself of all changes within the scope of the appended claims.

Having thus described my invention, what I claim as new and desire to secure by United States Letters Patent is:

1. In a guard, a curved frame of fiber board of substantially oblong shape and having a plurality of apertures in its edge, a strip of felt curved about the edge of said frame, stitching passing through said apertures and both edges of said felt, and flexible means located within the arc of said felt, whereby said flexible means is maintained out of contact with the body of the wearer and tensioned between different points on the curved surface of said frame to reinforce the same.

2. In a guard, a curved frame of fiber board of substantially oblong shape and having a plurality of apertures in its edge, a strip of felt curved about the edge of said frame, stitching passing through said apertures and both edges of said felt, means tensioned between different points on the curved surface of said frame to reinforce the same, a fabric pocket to receive said guard, and tension means on said pocket supporting said guard on the body of a wearer.

3. In a guard, a supporting device comprising a pocket formed of fabric and open at the top, elastic means extending from two edges of said pocket about a limb of the wearer, said pocket having a plurality of spaced apertures through both sides of the same along the top edge, and lacing for closing said pocket and securing the same to another garment.

4. In a guard, the combination of a curved frame member of relatively stiff material with a flexible steel tension member extending transversely to said frame member and secured thereto at a point between the edges of said curved member, said tension member being located on the outside curved surface of said curved member to reinforce the latter against strains tending to produce further curvature.

5. In a guard, the combination of a relatively stiff curved sheet with a flexible steel tension member passing transversely about a part of said curved sheet and secured thereto at a point between the edges thereof, the part of said tension member outside said curved sheet being adapted to resist further curvature, and the part of said tension member in-

side said curved sheet being adapted to resist flattening of said guard.

6. In a guard, the combination of a relatively stiff curved sheet with a tension member passing transversely about a part of said curved sheet and secured thereto at a point between the edges thereof, the part of said tension member outside said curved sheet being adapted to resist further curvature, and the part of said tension member inside said curved sheet being adapted to resist flattening of said guard, and means for protecting the edge of said guard and spacing said guard from the body of the wearer to prevent contact with said tension member.

7. In a guard, the combination of a relatively stiff curved sheet with a tension member passing transversely about a part of said curved sheet and secured thereto at a point between the edges thereof, the part of said tension member outside said curved sheet being adapted to resist further curvature, and the part of said tension member inside said curved sheet being adapted to resist flattening of said guard, and means for protecting the edge of said guard and spacing said guard from the body of the wearer to prevent contact with said tension member, comprising a strip of padding curved about the edge of said guard and secured thereto.

8. In a guard, the combination of a relatively stiff curved sheet with a tension member passing transversely about a part of said curved sheet and secured thereto at a point between the edges thereof, the part of said tension member outside said curved sheet being adapted to resist further curvature, and the part of said tension member inside said curved sheet being adapted to resist flattening of said guard, means for protecting the edge of said guard and spacing said guard from the body of the wearer to prevent contact with said tension member, comprising a strip of padding curved about the edge of said guard and secured thereto, and a support comprising a fabric pocket and a broad elastic band forming an elastic sleeve for securing said pocket on the limb of a wearer.

In witness whereof, I hereunto subscribe my name this 9th day of February, 1927.

DAVID LEVINSON.
